[57] **CLAIM**

The ornamental design for a plastic clamp, as shown and described.

DESCRIPTION

FIG. 1 is a perspective view of a plastic clamp showing my new design in its clamping position;
FIG. 2 is a top plan view thereof;
FIG. 3 is a bottom plan view thereof;
FIG. 4 is a side elevational view thereof;
FIG. 5 is a front elevational view thereof;
FIG. 6 is a rear elevational view thereof; and,
FIG. 7 is a side elevational view thereof shown in its fully retracted non-clamping position.

FIG. 2.
